UNITED STATES PATENT OFFICE

2,271,912

DIVIDED SHANK RAIL FASTENER

Ralph P. Clarkson, New Rochelle, N. Y.

Original application June 29, 1935, Serial No. 29,052. Divided and this application February 16, 1938, Serial No. 190,793

7 Claims. (Cl. 238—349)

This invention relates to divided shank rail fasteners, more particularly that type or kind of rail fastener in which the rail is resiliently clamped or held to a tieplate or other supporting means or in which the rail is directly clamped to the tie or other cross member, the fastener being anchored in the tie or engaging below the rail support, as desired.

It is a general object of this invention to provide a novel and improved balanced track construction including a rail fastener which is simple in design, easy to manufacture, low in cost, and efficient in operation; which permits the continued use of the present tieplates; by means of which there is produced a stronger, safer, and more easily and economically maintained track structure than those now in general use; which permits required wave motion in the rail without transmission of this motion to the supporting structure; which distributes the load on the tieplate without tendency to rock the plate and thus, in fact, prolongs the life of wooden ties; and which particularly lends itself to simple installation in present track structure with ordinary tools and labor and without special equipment.

More particularly it is an object of the present invention to provide a rail fastener by means of which the rail is held to the tieplate or other support by the spring action or resilient effect of a bifurcated or two part shank fastener which may be readily driven into position and which requires no bolts or nuts for fastening or flexing, no special tools for installation or removal, and which may be employed with the present widely used, ordinary rolled tieplates with single or double shoulders or without any shoulders at all, and which is adapted to hold the tieplate to the tie as well as to hold the rail, particularly from creeping or longitudinal movement.

Thus any present tieplate may readily permit the application of the principles of the present invention. It is apparent that this feature, combined with the low cost of the fastener and ease of installation, facilitates changing over present track construction to the more modern continuous welded rail construction, as it may be done without discarding any present track equipment but merely by substitution of these fasteners.

A further object of the present invention is to provide a rail fastener of the type described which is so constructed and positioned that the movement of the rail presents no effective component of force in line with the withdrawal direction of the fastener and there is substantially no maintenance required, such as continual

tightening, and yet the fastener may be removed and replaced when necessary or desirable.

From the standpoint of economy, besides the elimination of ever costly maintenance, it may be further pointed out that the construction provided by this invention will prevent the rail from creeping and thus preclude the necessity of the provision of additional rail anchors or anti-creepers.

Another important feature of this invention permits the use of a divided shank spike involving this invention as the ordinary rail spike is used, leaving the rail free with gauge maintained and in addition the tieplate is clamped in place.

With the foregoing and other objects in view as will be apparent to those skilled in the art as the description proceeds, my invention resides in the combination and arrangement of parts and in the details of construction described in this specification and particularly pointed out in the appended claims, it being understood that changes may be made in the particular embodiment of the invention within the scope of what is claimed without departing from the spirit of the invention. I intend no limitation other than those of the claims when fairly interpreted in the light of the full disclosure and the present state of the art.

Reference is made to my copending application Serial No. 29,052, filed June 29, 1935, of which this application is a division and I also refer to my copending application Serial No. 65,945, filed February 27, 1936.

Referring now to the accompanying drawing which is furnished for illustrative purposes, it is apparent that various modifications in the embodiment of my invention are possible, of which several are shown by way of example, including a form at present preferred.

In the drawing, Fig. 1 is a fragmentary transverse section illustrating an application of my invention to the type of construction with rail mounted on metal cross members, in this case an angle or the like steel shape.

Fig. 2 is a sketch illustrating one form of rail fastener involving my invention applied in Fig. 1.

Figs. 3 and 4 are fragmentary sectional details illustrating the applications of a preferred form of rail fastener involving my invention.

Figs. 5 and 6 are plan views of rail and tieplate assembly illustrating the applications of the form of fastener shown in Figs. 3 and 4.

Fig. 7 is a view similar to Fig. 1 illustrative of a modified form of rail fastener in use.

Fig. 8 is a sketch illustrative of the fastener of Fig. 7.

Similar reference characters refer to corresponding parts in the several views.

The present invention is illustrated as applied to standard forms of railway rail indicated generally by the numeral 10 and provided with the usual parts including base flanges 12 and 13. A standard tieplate 1 may be of any type and preferably extends beyond the base flanges of the rail 10. The tieplate may be held to the cross tie by separate reversed rail fasteners (Figs. 4 and 5), by the rail fastener itself (Figs. 3 and 6), or otherwise as may seem desirable. Normally, in street railway construction, the rail 10 (Fig. 1) rests directly on a cross member 2 which may be any steel shape or metal tie.

While my invention may be utilized in any construction regardless of the type of tieplate used, I prefer to employ a double shouldered or channel type of tieplate. I prefer that the rail seat 9 be cambered to provide line contact transversely between the rail and the rail seat. The preferred passage 3 provided for the rail fastener is such as to permit the use of a rail spike therein, if desired. Preferably the driven leg (8, 8a) is of rail spike width and engages the side walls of the passage 3 to prevent twisting. My invention contemplates the provision of additional openings 3 (Figs. 5 and 6) in each tieplate to one side of the rail seat and spaced from the resilient rail fastener so that a rail spike may be used simultaneously with the rail fastener, if desired.

One embodiment of my invention, illustrated in Fig. 1, in fragmentary section, shows one side of a standard heavy rail construction wherein a rail 10 rests on a metal tie 2 and is resiliently held by one or more bifurcated or divided shank drive fasteners each of which preferably has a straight, more or less rigid driven leg 8 and, in this embodiment, a resilient rail leg 7 integral with the driven leg and engaging the top surface of a rail flange 13. The lower end of the driven fastener is anchored in position, the fastener being preferably tilted away from the rail. In the instance shown, the under side of the tie flange 2 acts as the terminal or locking surface, corresponding to the under surface of a tieplate, which permits the bent or hooked end 5 of the driven member 8 to anchor the fastener.

The form of rail fastener of the bifurcated type illustrated in Fig. 1 and in Fig. 2, is a split bar with legs spread apart, engaging respectively the base flange 13 and the tie flange, the upper ends of the two shank members 7 and 8 being integral to form a driving head at the upper free end 6.

Such a fastener, however, I prefer to form from a flat plate of spring steel, bent double as in Figs. 7 and 8, preferably rustless, and the finished fastener is carefully spring tempered. Various modifications in the particular form of the fastener are shown in accompanying figures, embodying my invention, as will be described. All, however, comprise a two part shank including a driven leg and a pressure leg resiliently coacting, the fastener in each case being a driven type and provided with a driving head so that the force applied thereto may be applied in the line of direction of, or the line of divergence of, the driven leg.

I prefer at present, especially where gauge must be maintained by the fastener and a tieplate and wooden tie is used, to use a divided shank drive fastener of the form shown in Figs. 3, 4, 5, 6, which may be driven through the tieplate open-

ing 3 and anchored in the tie, preferably in canted position (Fig. 3), the drive leg bearing on the tieplate 1, holding the latter firmly to the tie while the rail leg 7 resiliently engages the upper surface of the base flange 13 of the rail so as to yieldingly clamp the rail base to the rail seat of the tieplate and, while permitting wave motion of the rail, such construction acts to resist longitudinal creeping or side motion. The same type of rail fastener may be reversed and used (Fig. 4) for yieldingly holding down the tieplate while leaving the rail free to move up and down. Fig. 5 illustrates the combined use of four such drive fasteners, two preferably at the longitudinal center of the tieplate 1 holding down the tieplate resiliently and maintaining gauge (as in Fig. 4) and one rail fastener on each side of rail 10 with resilient fingers engaging the rail base at points removed from said center line in the manner of Fig. 3. In the case of cambered plates the center line is in the line of contact between rail and tieplate.

For a balanced construction it may be preferred and, of course, will be cheaper, to use a single rail fastener on each side of the rail 10, as in Fig. 6, the pressure arm 7 of the fastener acting to resiliently clamp the rail base to a tieplate 1, the driven arm 8a preferably wedging into the tieplate opening 3 (shown in Fig. 3) and the fastener being anchored below the rail 10 in the rail supporting tie.

It is apparent that in the construction of Figs. 3 and 4, as well as in that of Fig. 1 and other embodiments of my invention illustrated, the driven member 8, 8a, 8b, of the rail fastener may be canted at an angle to the motion produced in the rail by passing traffic and because of the coaction between the legs as well as the cantilever action of the rail engaging member, the driven member is not loosened by the wave motion of the rail nor is the tieplate holding means loosened, any upward lift of the rail actually tending to force the drive leg more firmly against the tieplate. In other words, in all the constructions shown, the rail may have wave motion under traffic conditions and this motion is not imparted to the tieplate which is held firmly to the tie.

In the particular embodiment shown in Fig. 7, the form of rail fastener used engaging base flange 12 and shown clearly in Fig. 8, may be provided with a raised portion 4 on the driven leg 8b to provide a stop for the edge of the rail base. This permits the leg 8b to be thinner in section than would otherwise be the case if the opening 14 extends out from the rail seat a considerable distance, and thus the raised portion compensates for the thinness of the leg.

What I claim is:

1. As an article of manufacture for securing a rail to its support, a bifurcated spike comprising two resiliently cooperating shank members, said members being formed by a longitudinally divided shank, one of the shank members being curved laterally away from the other member and forming an elongated, resilient, hold-down member, the shank members being connected at one end.

2. As an article of manufacture, a drive type rail fastener for resiliently clamping a rail to its support provided with a driving head portion at the upper end and a shank divided therebelow to form two resiliently cooperating, elongated members integral at said head portion and both downwardly extending therefrom, the dividing point of said shank being above the rail support when

said fastener is positioned and one of said shank members overlying said rail.

3. In a railroad track construction, in combination, a rail and a support therefor including a tie-plate with the usual spike openings and a wooden tie, a one-piece spike extending through one of said spike openings and anchored in said tie, the shank of said spike separating in a plane extending longitudinally of the shank into two members, one of said shank members being elongated and extending sidewardly away from the other member and resiliently engaging the upper surface of the base flange of said rail, and the other of said shank members substantially straight and engaging said tieplate and pressed thereagainst by any upward force of said rail on said first mentioned shank member.

4. In a railroad track construction, in combination, a rail, a tieplate, a tie, a resilient rail fastener on each side of said rail anchored in said tie, the shank of said fastener separating into two members including an elongated pressure leg extending sidewardly away from the other part and resiliently clamping said rail to said tieplate to restrain longitudinal motion of said rail relative to said tieplate, and a portion of said shank wedging into said tieplate opening to prevent upward motion of said tieplate.

5. Elastic rail spike for securing railway rails to wood ties, comprising a shank separating in a longitudinal plane through the shank into two parts, one of said parts being curved sidewardly away from said other part to form an elongated, resilient gripping arm.

6. As an article of manufacture, a drive type rail fastener for resiliently clamping a rail to its support, said fastener comprising a head and 10 a pair of members disposed below the head, said members being integrally connected at one end, one member being constructed to secure the fastener to a rail support and the other member being curved laterally from the first member and 15 forming an elongated, resilient, hold-down member.

7. In a railroad track construction, in combination, a rail and a support therefor including a tie-plate and a wooden tie, a spike extending through an opening in said tieplate and anchored 20 in said wooden tie and provided with a two part shank, one member of said shank projecting sidewardly away from the other member and forming an elongated, resilient member overlying said rail and resiliently clamping said rail to said tieplate.

RALPH P. CLARKSON.
